DOLL EYE

David Cohn, Brooklyn, N. Y., assignor to Mardon Corporation, Newark, N. J., a corporation of New Jersey

Application October 11, 1945, Serial No. 621,816

7 Claims. (CL. 46—169)

1

This invention relates to doll eyes.

The prime object of the present invention is to produce doll eyes, especially of the movable type, embodying an improved structure and introducing improved manufacturing methods.

Heretofore, doll eyes have been made in either inexpensive or expensive forms. The inexpensive form consisted simply of a sheet metal shell lithographed and colored to simulate the eyelid, eyeball and iris of the eye. Such eyes lack the lustre and depth of the more expensive eyes. The latter were made of different types, the most common form comprising an eye made of two parts consisting of a shell made of sheet metal cut out at the center to receive a transparent lens or iris usually made of a plastic material. In this form, the metal eye shell has to be made to simulate both the lid (when the eye is moved to sleeping position), and the eyeball (when the eye is moved to open position); and the metal shell, therefore, has to be lithographed and colored in two different colors, namely, flesh color for the lid simulation, and white color for the eyeball simulation.

The disadvantages encountered in the manufacture of this described form of the more expensive doll eyes are many. The coloring (enamel coating) of the eye shell has to be done in one or more operations before shell-shaping. If either of the differently colored coatings of the eye shell is damaged during shaping, as for instance by scratching or abrading, the whole eye shell has to be discarded. The colored coatings are but superficial and hence impart an artificial appearance to the eye. The metal shell after being shaped has to be embossed to form a seat for the plastic iris or lens, and the iris has to be secured in place by peening or forcing the eye opening edge material of the shell over or into the plastic iris. These forming and assembling operations are difficult, require skill, and often damage and mar the eye.

The doll eye of the present invention has been designed to obviate these structural and manufacturing drawbacks and to more effectively solve the problems involved.

In accordance with the present invention, the doll eye is constructed and designed so that:

1. The doll eye is made to comprise three separate parts, an eyeshell, an eyeball and an iris, these three parts being differently colored to simulate the three different elements of a movable type of doll eye, namely the eyelid, the eyeball and the iris;

2. This three-part eye is preferably made as an all-plastic eye so that these three parts may

be produced as colored plastic moldings, making subsequent coloring operations unnecessary and producing a color depth for all of the eye parts which imparts to the eye a desired natural appearance;

3. Each of these three parts is formed or molded to the finally needed shape, so that the eye may be assembled without further forming operations, as by merely assembling or putting together the eye parts; and

4. This three-part eye is so constructed that eyelash members may be readily assembled thereto to produce an improved type of eyelash doll eye.

To the accomplishment of the foregoing objects and such other objects as may hereinafter appear, my present invention relates to the doll eye sought to be defined in the appended claims and as described in the following specification taken together in the accompanying drawings in which:

Fig. 1 is a vertical section taken through a doll head, the view showing an eye set containing one of the eyes of the present invention, the doll head being shown in vertical position and the eye in an open condition;

Fig. 2 is a vertical section similar to Fig. 1, but showing the doll head in a reclined position and the eye in a sleeping condition;

Fig. 3 is an exploded view, taken on an enlarged scale, of the doll eye of the present invention, showing the three separate parts thereof, two parts of the three-part eye being shown in section;

Fig. 4 is a fragmentary part of a detail embodying a modification;

Fig. 5 is an enlarged partially sectioned view of the assembled eye, the section being taken in the plane of the line 5—5 of Fig. 6;

Fig. 6 is a front elevational view of the eye shown in Fig. 5;

Fig. 7 is a top plan view illustrating an eye mounting;

Fig. 8 is a horizontal partially sectioned view of an eye, this view showing a different eye set mounting for the eye and thus embodying a modification of the eye structure itself; and

Fig. 9 is a partially sectioned view of the modification of Fig. 8, taken in the plane of the line 9—9 of Fig. 8.

Referring now more in detail to the drawings, and having reference first to Figs. 1 to 3 and 5 and 6 thereof, the doll eye of the present invention comprises a three-part eye consisting of an eye shell generally designated as S provided with

55 a front opening 10, said eye shell being adapted

to be fitted into and to rotate within the eye socket 12 of a doll head H, an eyeball part B having a front opening 14, the eyeball part B being inserted into and mounted in the opening 10 of the eye shell S, and an iris or lens part I inserted into and mounted in the opening 14 of the eyeball part B, these three parts being shown in exploded condition in Fig. 3 of the drawings and in assembled condition in the remaining figures of the drawings.

The eye shell S is colored to simulate an eyelid, the eyeball part B is colored to simulate the ball of an eye and the iris part I is colored to simulate the lens and pupil of the eye. The eyeball part B has an outside contour (its meeting edge with the opening of the eye shell S) which corresponds to the contour of the opening of the eye socket 12, as best shown in Fig. 6 of the drawings. The eye shell, eyeball and iris are otherwise so constructed that the outside faces of the same lie in a continuous spherical surface, as best shown in Figs. 1, 2 and 5 of the drawings. With this construction, it will be observed particularly from Figs. 1 and 2 of the drawings, that when the doll head is in the vertical position with the eye in open condition, only the eyeball B will be visible through the eye opening of the doll head, and that when the doll head is in the reclined position, with the eye in the sleeping condition, the eye shell S, colored to simulate the eyelid of the eye, will be exposed and visible at eye opening of the doll head. To accomplish the results the eye shell S is colored with a flesh color to simulate the eyelid, the eyeball part B is colored white to simulate the ball of the eye and the iris part I is suitably tinted to simulate the blue or brown color of the lens of the eye. This three-part structure of the doll eye thus enables the different individual coloring of the eye shell, eyeball and the iris to meet or satisfy the needs or conditions met with in the manufacture of a movable type of doll eye.

Preferably, and to follow out the additional advantages secured by the present invention, each of these three parts which compose the final doll eye, namely: the shell S, the ball part B, and the iris part I is made of a plastic material. The desired color, particularly for the eye shell S and the eyeball part B, is imparted to the eye in the making of the plastic pieces (the shell and the ball part). The desired color may also be imparted during the molding operation of the iris I, but preferably the color is imparted thereto by a separate operation to be described hereinbelow, this being preferred for the purpose of giving the desired depth and lustre to the iris or lens of the eye. The making of these parts, particularly the eye shell and the ball part, as colored plastic units or molded pieces makes unnecessary any subsequent coloring operations and moreover produces a color depth for these parts which imparts to all of the eye parts a desired very natural appearance.

This three-part all-plastic doll eye is furthermore so preferably constructed that the three parts may be assembled to produce the doll eye merely or solely by the inserting and mounting of the eyeball part into the eye shell and the iris part into the eyeball part. This will be best seen by comparing Figs. 3 and 5 of the drawings. Either the eyeball part B and the iris I are first assembled together and this pre-assembled eyeball-iris structure is assembled to the eye shell S, or the eyeball B is first inserted and mounted into the eye opening 10 of the eye shell S and

the iris part is then inserted and mounted into the opening 14 of the eyeball part B. These parts, particularly when made of a plastic material, have engaging walls which are thick enough and which are sufficiently resilient so that these parts may be thus assembled and interlocked simply by inserting one element into the other in this telescoping fashion, without the necessity of any additional forming or fastening operations.

This three-part doll eye is furthermore so designed and constructed that eyelash members may be readily assembled thereto to produce an improved type of eyelash doll eye. The production of eyelash doll eyes has in itself been a major problem in the art of doll eye manufacture. In the structure of the present invention, an eyelash member L of usual or known type is assembled to the eye merely by being inserted and held between the eye shell S and the eyeball part B. The manner of assembling the parts of this eyelash member will be best evident by examining Figs. 3 and 5 of the drawings. The eyelash member L after being placed in its curled or concaved condition into the opening 10 of the eye shell at its eyelash position therein is clamped in this position by the insertion of the ball part B in the shell opening 10. The eyelash is, therefore, secured in position by this assembling and clamping operation, making it unnecessary to employ adhesive and an adhesive applying operation now commonly used in the art. Furthermore, with this construction, an eyelash type of doll eye is produced without the use of shell slitting operations and without the use of added lid members which are so disadvantageous in prior structures and which have been commonly used in the building of eyelash type of doll eyes.

The parts of the three-part eye when made of plastic material may be given the shape and configuration, best shown in Fig. 3 of the drawings. The eye shell S in addition to being formed with the front opening 10 is formed with a mounting seat 16, centrally apertured as at 18. The ball part B is outwardly contoured as at 20 to be received by the shell seat 16, and is inwardly contoured as at 22 to form a seat for the iris I, this ball part being also centrally apertured as at 24. The iris part I, spherically curved at its outer face 26, is contoured as at 28 to be received by the seat 22 of the eyeball part B and is provided centrally with a cylindrical or plug part 30 adapted to be fitted into the aperture 24 of the eyeball part B and to be exposed at its rear at the aperture 18 of the eye shell S when the parts are assembled together as shown in Fig. 5 of the drawings. The engaging walls of these eye parts are adapted to have a close or press fit, but preferably there is a clearance between the wall 28' of the iris I and its seat 22' of the eyeball part, and there is a clearance between the wall 20' of the eyeball part and its seat 16' of the eye shell to facilitate the manufacture and assembly of the parts.

In the form of the invention shown in Fig. 5 of the drawings the eyelash L is shown with its mounting end 32 kinked over the corner 34 of the eyeball part to help anchor the eyelash in place. In the modification shown in Fig. 4 a special recess 36 is formed in the eye shell S' to receive the mounting end of the eyelash member L', which recess locates the eyelash during its attachment.

After assembling the parts of the eye, the plug protruding end 30 of the iris part I is preferably sprayed with a black cementing fluid to provide a black pupil center 38 for the iris or lens I. The cementing fluid may at the same time serve to ce-

ment the eyelash, the eyeball part, the iris and the shell together, although this additional attaching or cementing is unnecessary where the parts are made from a plastic material. As a cementing fluid, any solvent for the plastic material may be used. The cementing fluid is indicated in Fig. 5 by the heavy shading 40; its effect to cement the parts together is also indicated in this figure and its effect in creating a dark pupil center 38 for the eye is indicated in Fig. 6 of the drawings.

In Figs. 5 and 7 (as well as in Figs. 1 and 2) a commonly known eye mounting is shown for this doll eye comprising a metal plate 42 for each eye, the metal plate being carried by a frictional fitting axle 44, the purpose for this kind of mounting being to allow the eyes to be adjusted to the eye openings in a doll head.

The modification shown in Figs. 8 and 9 of the drawings employs instead of the metal plates 42, ribs 46, 46 which are molded integrally with the eye shell S². In mounting the eye of Figs. 8 and 9, the axle 44' is forced through one wall of the eye shell and then into the ribs 46, 46. The other parts of the eye shell of this modification are otherwise similar to the parts described in connection with Figs. 1 to 6 of the drawings and are, therefore, designated by similar reference characters differentiated by the exponent 2, the walls of some of the parts being, however, differently contoured.

The structure of the doll eye of the present invention and the manner of making the same and the advantages flowing therefrom will in the main be fully apparent from the above detailed description thereof. It will be further apparent that while I have shown the invention in the preferred forms, that many changes may be made in the structure thereof without departing from the spirit of the invention defined in the following claims.

I claim:

1. A doll eye comprising an eye shell having a front opening, said eye shell being adapted to be fitted into and to rotate within the eye socket of a doll head, an eyeball part having a front opening, the eyeball part being inserted into and mounted in the opening of the eye shell, and an iris part inserted into and mounted in the opening of the eyeball part, the eye shell being colored to simulate an eyelid, the eyeball part being colored to simulate the ball of an eye, and the iris part being colored to simulate the lens of an eye.

2. A doll eye comprising an eye shell having a front opening, said eye shell being adapted to be fitted into and to rotate within the eye socket of a doll head, an eyeball part having a front opening, the eyeball part, having an outside contour corresponding to the contour of the shell opening, being inserted into and mounted in the opening of the eye shell, and an iris part inserted into and mounted in the opening of the eyeball part, the outside faces of the eye shell, the eyeball part and the iris part lying in a continuous

spherical surface, the eye shell being colored to simulate an eyelid, the eyeball part being colored to simulate the ball of an eye, and the iris part being colored to simulate the lens of an eye.

5 3. A doll eye comprising an eye shell having a front opening, said eye shell being adapted to be fitted into and to rotate within the eye socket of a doll head, an eyeball part having a front opening, the eyeball part being inserted into and mounted in the opening of the eye shell, an iris part inserted into and mounted in the opening of the eyeball part, and an eyelash member inserted and held between the eye shell and the eyeball part, the eye shell being colored to simulate an eyelid, the eyeball part being colored to simulate the ball of an eye, and the iris part being colored to simulate the lens of an eye.

20 4. An all-plastic doll eye comprising an eye shell having a front opening, said eye shell being adapted to be fitted into and to rotate within the eye socket of a doll head, an eyeball part having a front opening, the eyeball part being inserted into and mounted in the opening of the eye shell, and an iris part inserted into and mounted in the opening of the eyeball part, the eye shell, eyeball part and iris part comprising separate elements before assembly, each made of a plastic material, the eye shell being flesh colored to simulate an eyelid, the eyeball part being white colored to simulate the ball of an eye, and the iris part being colored to simulate the lens of an eye.

25 5. The all-plastic doll eye of claim 4 in which the three separate eye shell, eyeball and iris elements are shaped so as to be assembled and held together solely by interfitting relationship by frontal insertion of the eyeball part into the eye shell and the iris part into the eyeball part.

30 6. An all-plastic doll eye comprising an eye shell having a front opening, said eye shell being adapted to be fitted into and to rotate within the eye socket of a doll head, an eyeball part having a front opening, the eyeball part being inserted into and mounted in the opening of the eye shell, an iris part inserted into and mounted in the opening of the eyeball part, and an eyelash member in addition to said eye inserted and held between the eye shell and the eyeball part, the eye shell, eyeball part and iris part comprising separate elements before assembly, each made of a plastic material, the eye shell being flesh colored to simulate an eyelid, the eye ball part being white colored to simulate the ball of an eye, and the iris part being colored to simulate the lens of an eye.

35 7. The all-plastic doll eye of claim 6 in which the eye shell, eyeball part, the iris part and the eyelash member are shaped so as to be assembled and held together solely by interfitting relationship by frontal insertion of the eyeball part into the eye shell and of the iris part into the eyeball part with the eyelash member inserted between the eye shell and the eyeball part.
